CLAIM

The ornamental design for a handheld X-ray scanner as
shown and described.

DESCRIPTION

FIG. 1 is a rear, left side, and top perspective view of a
handheld X-ray scanner showing our new design;
FIG. 2 is a rear, right side, and bottom perspective view
thereof;

FIG. 3 is a front, left side, and top perspective view thereof;
FIG. 4 is a rear view thereof;

FIG. 5 is a front view thereof;

FIG. 6 is a right side view thereof;

FIG. 7 is a left side view thereof;

FIG. 8 is a top view thereof; and,

FIG. 9 is a bottom view thereof.

In the drawings, the broken lines represent portions of the
article that form no part of the claimed design.

1 Claim, 9 Drawing Sheets
